GEE, OKLAHOMA, A CORPORATION.

WRNCH.

1,101,381.

Specification of Letters Patent. Patented June 23, 1914.

Application filed April 23, 1913. Serial No. 769,126.

To all whom it may concern:

Be it known that we, ANTON T. ANDERSON, FRANK L. BAILEY, and WILLIAM C. CUMMINGS, citizens of the United States, residing at Okmulgee, in the county of Okmulgee and State of Oklahoma, have invented certain new and useful Improvements in Wrenches, of which the following is a specification.

This invention relates to improvements in wrenches of the particular type shown in the co-pending application Serial Number 787,589, filed December 18th, 1912, of Anton T. Anderson.

The object of the present device is the provision of a wrench comprising an adjustable head mounted upon a handle, with means for controlling the movement of said head whereby the latter may be held in a stationary position or upon initial movement of a controlling member to permit free swinging movement of the head and upon continuation of the movement of said controlling member to limit the swing of the head to one direction only. To this end our wrench is provided with head engaging members normally tending to hold the same stationary with which members a controlling lever coöperates in a manner which will be more clearly understood as this description proceeds.

With the above and other objects in view, this invention consists in the construction, combination and arrangement of parts all as hereinafter more fully described, claimed and illustrated in the accompanying drawings, wherein—

Figure 1 is an edge view of a wrench constructed in accordance with our invention. Fig. 2 is a longitudinal sectional view taken about on the plane indicated by the line 2—2 of Fig. 1, and showing the position of the coöperating members when the head of the wrench is held stationary. Figs. 3 and 4 are fragmentary sectional views showing the co-operation of the controlling lever with the head engaging members to permit ratchet movement of the head on its pivot in either direction. Fig. 5 is a fragmentary view showing more clearly the intermediate position assumed by the pawls under action of the controlling lever.

Throughout the following detail description, and on the several figures of the draw-

ings, similar parts are referred to by like reference characters.

Referring to the drawings the numeral 1 designates a handle which terminates at one end in a pair of spaced arms 2, 2, between which arms is pivotally mounted a jaw head 3. The head 3 is of circular form and adapted to swing upon its pivots 4 projecting inwardly from the arms 2 so as to present its jaws in various positions whereby to manipulate nuts or other rotatable parts disposed in difficultly accessible positions. The peripheral portion of the head is provided with ratchet teeth 5 and said head also consists of a stationary jaw 6 with which a movable jaw 7 is adapted to coöperate. The movable jaw 7 is provided with a shank 8 which is adapted to move in a guideway 9 under action of an actuating worm 10 rotatably mounted in a recess 11 upon a shaft 12, said shank 8 being provided on its inner edge with the coöperating worm teeth 13 meshing with said worm 10. The means for controlling movement of this head 3 is disposed between the head and the handle 1, and also between the arms 2, as clearly shown by reference to Figs. 2, 3 and 4 of the drawings. Said means consists of a pair of head engaging members or pawls 14 spaced apart so as to engage the ratchet teeth 5 of the head at opposite sides of the same. Each of these pawls 14 is pivotally mounted intermediate its ends upon the pins 14' adjacent the head 3 so that its free end 14" will engage the ratchet teeth 5, said end being normally held in engagement with the head under the action of the expansion spring 15 which is disposed between the opposite ends of the pawls in an apertured partition 15'. This spring is normally under compression for this purpose and the pawls 14 are preferably formed with seats 16, shown in Fig. 2 most clearly, to properly hold the spring in its relative position. Each of the pawls, furthermore, is formed on its outer edge opposite the seats 16 with a recess 17, the end of the pawl terminating adjacent the recess in a nib 18 extending substantially at a right angle to the pawl. Adapted to coöperate with the pawls 14 is a controlling lever or latch 19 pivotally mounted upon the pivot 20 adjacent the terminal nibs 18 of said pawls. The controlling lever terminates at its ends in hook members 21 which are

adapted to engage over the nib 18 of the adjacent pawl 14 in controlling the action of the head 3.

In operation the wrench head 3 is normally held in a stationary position by the engagement of the pawls 14 with the ratchet teeth 5, by virtue of the tension of the spring 15 against the inner ends of said pawls. When it is desired to permit free swinging 10 movement of the head to a convenient position for operating upon a nut the controlling lever 19 is moved slightly in one direction on its pivot so that one of its hook members 21 will contact with the lower end of 15 the adjacent pawl to a sufficient extent to bring the free end of this pawl out of engagement with the teeth. The opposite hook member 21 of the lever 19 by this movement aforesaid has been caused to ride out 20 of the recess 17 of the opposing pawl upon the nib 18 of the latter whereby the last mentioned pawl will also be held from engagement with the ratchet teeth. When the position of the head has been determined 25 with respect to the handle continued movement is imparted to the controlling lever in the direction just given whereby the first-mentioned pawl is swung away from the head into a position shown most clearly in 30 Fig. 3 and the opposing pawl is entirely disengaged by the controlling lever as the terminal hook member leaves the nib of the same, whereupon said opposing pawl engages the teeth 5 of the head. Ratchet 35 movement may thus be permitted in one direction in an obvious manner, the inner face of the free end of each pawl being beveled so as to permit free sliding action of its engaging face. To permit ratchet move- 40 ment of the head in the opposite direction the lever pawl is moved in the reverse direction to that above described as will be clearly understood by those skilled in the art to which this refers.

45 It will be apparent from the foregoing that this arrangement of the coöperating parts of the wrench is distinctly advantageous when it is used to manipulate a nut in a place comparatively difficult to permit 50 of free access, because of the fact that it is not necessary to remove the wrench head from engagement after it has once been applied to turn the nut in either direction. It is also particularly desirable that the 55 wrench head be normally held stationary and susceptible of control for use as a ratchet wrench as well as allowing the head to be fixedly positioned at various angles with respect to the handle when so desired.

60 With the foregoing in view it is obvious, referring to Fig. 3, that the initial movement of the controlling lever 19 will operate the spaced pawls so as to bring them into the dotted line position shown in said figure 65 and that the continued movement of the

lever will permit the pawl at the right of the wrench to assume its former position while the pawl at the left is swung quite clear as shown in full lines, the pressure of the spring 15 being exerted against the pivot 70 of the last mentioned pawl whereby said lever and pawl will retain their position until the action of the lever is reversed and the spring allowed to act against the lower end. 75

Having thus described the invention, what is claimed as new is:

1. In a wrench, the combination with a handle and a jaw head pivoted thereto and having ratchet teeth, of spaced pawls adapted to coöperate with the head, each of said pawls being pivotally mounted between its ends and terminating in a nib, a controlling lever common to both pawls pivotally mounted intermediate its ends and terminating in hook members, the hook member at one end of said lever being adapted to engage one of the pawls to hold the free end disengaged from the head on initial movement of said lever and the hook terminal at the other end of said lever being adapted to engage the nib of the other of said pawls to hold the free end of the latter from engagement with the head, the last mentioned hook terminal of the lever being adapted to be disengaged from the second mentioned pawl upon continuation of the movement of said controlling member, to permit ratchet movement of the head, and a spring disposed in the handle and pressing against the opposite ends of the pawls to normally hold the latter in engagement with the head, said spring being movable upon actuation of the pawls by the controlling lever whereby the pressure on one of said pawls is exerted in line with the pivot of the same to frictionally bind the pawl against said pivot and retain the former in disengaged position. 95

2. In a wrench, the combination with a handle terminating in spaced arms and a jaw head pivotally mounted between said arms, said head having peripheral ratchet teeth, of a pair of pawls mounted between said arms at opposite sides of the wrench, the free ends of said pawls being adapted to engage with the ratchet teeth at opposite sides of the jaw head aforesaid, the sides of the pawls at the ends opposite the ends engaging the jaw head being formed with nibs, a controlling lever pivotally mounted adjacent the last mentioned ends of the pawls and terminating in hook members normally engaging around the nibs when the pawls are engaged with the heads, one of said hook members being adapted to ride on the nib of its adjacent pawl to disengage the free end of the latter from the ratchet teeth upon initial movement of the lever and to be disengaged from the nib upon further movement of the lever to permit ratchet move- 120 125 130

ment of the jaw in one direction, an apertured partition disposed between the spaced arms, and a spring seated in the aperture of said partition and pressing against the ends 5 of the pawls to normally hold the latter in engagement with the head, said spring being movable upon actuation of the pawls by the controlling lever whereby the pressure on one of said pawls is exerted in line with the 10 pivot of the pawl to frictionally bind the

latter against said pivot and retain the pawl in disengaged position.

In testimony whereof we affix our signatures in presence of two witnesses.
